Charles du B. Arcularius, New Canaan, Conn., assignor to Laboratory Furniture Co., Inc., Long Island City, N. Y., a corporation of New York

Application September 22, 1949, Serial No. 5,128

Term of patent 14 years

(Cl. D91—3)

To all whom it may concern:

Be it known that I, Charles du B. Arcularius, a citizen of the United States and a resident of New Canaan, county of Fairfield, and State of Connecticut, have invented a new, original, and ornamental Design for a Valve Knob, of which the following is a specification, reference being had to the accompanying drawing, forming a part hereof, in which:

Figure 1 is a perspective view of a valve knob embodying my new design;

Figure 2 is a top plan view of the valve knob shown in Figure 1; and

Figure 3 is an elevational view of the valve knob, as seen from the front of Figure 2.

I claim:

The ornamental design for a valve knob, as shown.

CHARLES DU B. ARCULARIUS.
